UNITED STATES PATENT OFFICE

2,441,345

PORTABLE FOOD CABINET

Luella Elnora Brubaker, Elkhart, Ind.

Application November 1, 1944, Serial No. 561,386

1. Claim. (Cl. 190—12)

1

This invention relates to suitcases or the like in general, and more particularly to cases adapted to carry a plurality of articles of a varied assortment, and aims to provide a suitcase having a shelf-like compartmented inner frame or cabinet equipped with doors on both sides and spaced laterally and at the top from the suitcase walls, the case also being equipped with hinged side walls to convert the same into doors.

The case of this invention would be particularly adaptable and suitable to people who live in furnished rooms or hotels.

The above and other objects will become apparent in the following description, reference being had to the accompanying drawings wherein characters of reference refer to like-numbered parts in the description. It is to be understood that the drawings are intended for the purpose of illustration only, and that it is neither desired nor intended to limit the invention in any manner to the specific details of construction shown excepting insofar as they may be deemed essential to the invention.

Referring briefly to the drawings,

Fig. 1 is a perspective view of the suitcase with the doors partly open to expose the interior.

Fig. 2 is a side elevational view of the case with the doors open.

Fig. 3 is a cross-sectional view taken on the line 3—3 of Fig. 2.

Referring in detail to the drawings, the numeral 10 indicates the central portion or frame of the suitcase and comprises the top panel 11 provided with the handle 12, the side panels 13 and 14, and the bottom panel 15. Front and rear covers or doors 17 and 16, respectively, having inwardly turned flanges or overlaps 18, are hinged at 20 and 19, respectively, to the bottom panel 15. The usual strap ends are shown at 21, and they serve in the common manner to strap the case in closed condition.

Within the frame 10, a shelf-like compartmented inner frame 22 having the top panel 24, the bottom panel 23, and the side panels 25 and 26, and of the same depth as the frame 10, is mounted within the latter by securing the bottom panel 23 against the bottom panel 15 of the frame 10. Shelves 27 and 28 are mounted between the side panels 25 and 26; partitions 29 are provided between the panel 23 and the shelf 27; partitions 30 are provided between the shelves 27 and 28; and partitions 31 are likewise provided between the shelf 28 and the top panel 24. In the compartment 32 between the partitions 31 a drawer 33, having a handle 34, is mounted.

2

The frame 22 is open on both sides, and is provided on both sides with doors 36 and 37, respectively, which are hinged at the bottom to the bottom panel 23 of the frame 22. Eyelets or loops 38 and 39 are provided on the top panel 24 adapted to be engaged by hooks 40 and 41 on the doors 36 and 37, respectively, to hold closed these doors.

The suitcase is adapted to contain and carry 10 various items of food and the equipment required for preparing and preserving food, and may be conveniently used by persons living in a furnished room or a hotel who may wish to eat something between mealtimes, and the suitcase 15 may be used to provide a sanitary and presentable food container. The compartments between the shelf 27 and the bottom panel 23 would conveniently hold Sterno or canned heat, a collapsible Sterno stove, matches, waxed paper, etc. The 20 middle compartments could hold soda crackers, cheese, etc.; the drawer 33 could hold Dry Ice, frozen fruit, or articles wrapped in wax paper such as butter and cured meat. The above are of course only by way of example.

25 The boundary walls of the frame 22, excepting for the bottom panel 23, are, as is apparent, spaced from the adjacent walls or panels of the outer frame 10. This feature of construction permits of free circulation of air between the two 30 frames and also provides a heat insulation space between the frames.

To use the suitcase, one or both sets of doors on each side are opened down to horizontal position with the frame 10 standing upright, as 35 shown. The upper surface of the door 36 or 37 then provides a practical table-like area on which to serve the food, and the area of the upper surface of the door 17, Fig. 3, surrounding three sides of the door 36, provides a walled space for 40 setting articles of small size and particularly any which might be in danger of rolling off.

Obviously, modifications in form and structure may be made without departing from the spirit and scope of the invention.

45 I claim:

A portable case for carrying food comprising an outer frame, rectangular in shape, and having its opposite sides open, an inner frame within the outer frame and contiguous to the bottom of the 50 outer frame, said inner frame being of less width and height than the outer frame, thereby forming an inverted U-shaped air passage between both frames for the circulation of air, closures for the inner frame, said closures being hingedly connected to the bottom of the outer frame and

sufficiently large to close the opposite sides of the inner frame, closures hingedly connected to opposite sides of the lower portion of the outer frame and adapted to close opposite sides of the outer frame in spaced relation to the closures of the inner frame thereby allowing circulation of air between the closures, said closures of the inner frame being positioned whereby they will engage and be parallel to the closures of the outer frame when the outer frame closures are moved to 10 horizontal position.

LUELLA ELNORA BRUBAKER.
